DYNAMIC BALANCING SYSTEM FOR
ROTATING STRUCTURES

Paul Favrot, Lyon, France, assignor, by mesne assignments, to Landis Gendron S.A., Rhone, France, a company of France

Filed Feb. 19, 1962, Ser. No. 174,160
Claims priority, application France Feb. 28, 1961
8 Claims. (Cl. 74—573)

This invention relates to systems for dynamically balancing rotating mechanical members, a problem that arises in connection with any type of high-speed rotary machinery. Taking as an example the case of a high-speed revolving grinding wheel in a grinding or rectifying machine, the center of gravity of the wheel is liable to shift slightly off-center with time because of irregularities in wear coupled with minor non-uniformities in the density of the wheel material, and/or in the distribution of moisture in the pores of the wheel. At the high angular speeds involved, even very small off-center shifts in the center of gravity can result in the development of large centrifugal forces liable to cause a breakdown of the grinding wheel or other heavy revolving part concerned.

It has already been proposed to provide automatic dynamic rebalancing systems comprising essentially an annular recess filled with oil, for instance having the shape of a tore, formed in a member carried by a shaft and concentric to said shaft, this recess being divided by separation means in a certain number of chambers (usually 3 arcuate chambers extending each along 60°, while said separation means extend each along the same arcuate distance). In each of said chambers a movable mass is located, said mass being free to be displaceable along the wall of the chamber in which it is located, the chambers communicating with each other by passages extending through said separation means. The 3 passages above are connected respectively to 3 ducts provided in the shaft and opening radially in the oil film of the bearing, each of the pressure receiving openings being at 120° in respect to any one of the other openings. The pressure differentials created in the oil film of the bearing by an unbalance are transmitted to the corresponding chamber, so that the movable masses are supposed to move in respect to each other so as to compensate the unbalancing effect.

Unfortunately, the experience has proved that systems of the type above are not able to ensure the proper feeding of oil with the clearance provided in usual oil bearings due to the unsufficient output of oil supplied by the oil film of the bearing, said output being unsufficient for rapidly acting on the compensating masses in order to displace them according to the pressure variations. To increase said output it would have been necessary to increase considerably the pressure differentials acting on the pressure receiving openings of the ducts mentioned above and located at 120° in respect to each other (which would actually mean the increase of the value of the compensating signal). This result could only be obtained by an increase of the section of the clearance which would not be compatible with a proper operation of the rotating system. In addition, the low output mentioned above may induce to reduce the volume of the chambers (which could not be extended beyond 60°), so that the limited displacement of the balancing masses did not permit to compensate the balancing forces when these forces became high enough to be objectionable.

It is an object of this invention to provide an improved automatic dynamic re-balancing system for rotating mechanical members, which will have better performance characteristics than similar systems heretofore

2

available; objects are to increase the response rate of such systems and to ensure a more uniformly effective balancing action throughout the rotation of the rotary member.

5 In fulfilling these objects of the invention, there is provided in a dynamic balancing system of the type above defined, a plurality of circumferentially spaced recesses formed in the periphery of the rotating shaft within its bearing said recesses being equal in number to the plurality of movable elements, passage means connecting each of said recesses with a corresponding one of the balancing chambers, and means for supplying fluid under pressure to each recess and, consequently, to the corresponding interconnected balancing chamber. So, a body of fluid under pressure is interposed between said shaft and bearing, in the zone including said recesses, said body supporting at least partially said shaft in the manner known in "fluid type bearings."

In other terms, a bearing of the fluid type combined 20 with a balancing system permits to solve the difficult problem of feeding the annular recess practically, because it permits both to vary in the desired manner the output of the fluid and the value of the pressure differentials supplying the compensating signal, this type of bearing 25 being unaffected when mechanical clearances are relatively high, which again is due to the fact that the shaft is completely floating in the fluid under pressure without ever contacting the stationary mechanical parts.

Further objects of the invention relate to an improved 30 construction of the annular recess and the movable balancing elements therein. It is an object in this respect to provide an annular raceway structure which will be continuous around the circumference thereof so as to permit fully uninhibited flow of fluid and transmission 35 of pressure variations around the raceway for producing the compensatory shifting displacements of the movable elements along their arcuate path.

According to the invention, abutments are provided 40 inside the annular recess to positively limit the displacement of each compensating mass so that no separation means are necessary and a continuous annular recess takes place of the known arcuate chambers of a reduced length. It is also an object to provide an improved construction of the movable balancing elements, which 45 will ensure their smooth, free-floating, self-lubricated displacement along the continuous annular raceway in sealing engagement with the walls thereof, while rendering the manufacture of such elements simple and inexpensive.

50 It is still another object of the invention to supply fluid under pressure in parallel to each sustentation recess and corresponding balancing chamber.

The above and further objects and advantages of the 55 invention as well as the novel features thereof will appear from the description to follow, in which an exemplary embodiment of the improved dynamic balancing system is disclosed for purposes of illustration but not of limitation with reference to the accompanying diagrammatic drawings, wherein:

60 FIG. 1 is a view of the improved apparatus in axial section;

FIGS. 2 and 3 are cross sectional views respectively on the planes designated II—II and III—III in FIG. 1.

As shown an annular member 1 shown as a cylindrical 65 member is secured on a shaft 2 for rotation therewith. Shaft 2 is rotatably mounted within a bore in a smooth bearing member 3 by way of a fluid bearing later described. The shaft is here shown as being horizontal and the annular part 1 is mounted on an end of the shaft by way of a rigid assembly generally designated 4 and providing a housing within it for the active portion of a dynamic balancing or compensating system presently

described. The assembly 4 comprises a pair of parallel spaced flanges 5 and 6 and a spacer ring 7 positioned between said flanges adjacent the radially outer surfaces thereof, said flanges and ring being suitably secured by means not shown within the central bore of annular member 1. The assembly 4 is held in firm engagement against a shoulder 8 provided on shaft 2 by means such as a retainer nut 9 screwed on a threaded end part of the shaft.

There is thus defined within the assembly 4, internally of flanges 5 and 6 and ring 7 a continuous annular space of rectangular cross section. Disposed in this annular space or raceway are three movable reaction elements, preferably in the form of generally cylindrical rollers 11, 12, 13. The rollers are so dimensioned that they are freely displaceable along arcuate paths within the raceway while being at all times retained in positions such that their axes are parallel to the axis of the shaft 2. For this purpose the diameter of each roller is just slightly smaller, e.g. by an amount of the order of 0.02 mm., than the difference in radius between ring 7 and shaft 2, and the length of each roller is just slightly smaller, say by about the same amount of 0.02 mm., than the axial spacing between the inner faces of flanges 5 and 6.

The three rollers 11, 12, 13 define, in the continuous raceway, three compensating or balancing chambers 17, 18, 19. As will be apparent later the volumes of the three chambers are variable with the relative positions of the three rollers round the raceway. However, means such as stops 51, 52, 53 projecting from the inner periphery of ring 7 at 120 degree spacings therearound, are provided for positively limiting the arcuate displacements of the three rollers to arcs such that the positions of the three chambers cannot wander unrestrainedly around the circumference of the shaft for reasons that will later appear. To promote smooth frictionless displacement of the rollers along their arcuate paths, the opposite end faces of each roller are interconnected by a number of axial passages, herein shown as a central passage 57 and four passages 58 spaced around the circumference of the roller and connecting at their opposite ends with annular grooves 59 formed in the roller end faces.

Formed in the peripheral surface of shaft 2 within the axial extent of bearing sleeve 3 are three arcuate sustentation recesses 21, 22, 23 (see FIG. 3) which are of equal arcuate extent and are separated by equal arcuate distances. In operation fluid under pressure is maintained in the three recesses through means presently described. Fluid flowing out of the recesses is collected by three longitudinal grooves 31, 32, 33 formed in the periphery of shaft 2 intermediate the recesses as shown in FIG. 3, said grooves connecting at their opposite ends with a pair of circumferential channels 35 and 36 formed in the shaft beyond the ends of the recesses (see FIG. 1). The channels 35, 36 communicate with registering channels 37, 38 formed in the inner periphery of sleeve 3 from which the fluid is returned to a sump or exhaust.

Means are provided for supplying fluid under pressure in parallel to each of the balancing chambers 17, 18, 19 and a related one of the shaft recesses 21, 22, 23. As shown, a radial inlet passage 41 formed in the bearing sleeve 3 is adapted to be externally connected with a pressure source of said fluid, e.g. oil. The passage 41 delivers into a circumferential inlet manifold channel 42 formed in the inner surface of sleeve 3. Two or more radial passages 43 formed in shaft 2 connect the circumferential inlet manifold 42 with an axial bore 44 formed through the shaft 2. The outer end of bore 44 is adapted to be sealed with a screw plug as indicated on the left of FIG. 1. Also bored into the shaft around the axial passage 44 are three longitudinal, angularly spaced passages 26. Each of the passages 26 is connected near one end by way of a radial port 46 with the axial passage 44. Further, each passage 26 is connected by a radial

5

passage 25 with a related point of the continuous annular raceway, the three passages 25 being angularly equispaced 120° and being positioned opposite to the respective stops 51, 52, 53 (see FIG. 2) so as to deliver into each of the three balancing chambers 17, 18, 19, respectively regardless of the positions of the rollers. Moreover, each longitudinal passage 26 connects by another radial passage 27 with the center of a related one of the recesses 21, 22, 23.

Interposed in each longitudinal passage 26 between its connection 46 with the central bore 44 and its connection 25 with the raceway is an insert 47 providing a calibrated restricted orifice. Optionally another calibrated insert 30 is shown as inserted into each of the passages 25.

It will be evident from the description above that pressure fluid from inlet 41 flowing through inlet manifold 42, radial passages 43 and axial bore 44, is thence delivered in parallel, through a restriction such as 47, to each of the three balancing chambers 17, 18, 19 and the related shaft recesses 21, 22, 23. Effluent fluid from the shaft recesses is returned to the sump via grooves 31, 32, 33, channels 37 and 38 and the outlet shown.

The system operates as follows. Assuming the rotating assembly comprising shaft 2 and the annular part 1 (which be it noted may stand for any complex revolving assembly) is perfectly centered dynamically, i.e. its center of gravity is positioned accurately on the rotational axis of shaft 2, then the thickness of the fluid film between the adjacent surfaces of shaft 2 and bearing sleeve 3 is continually uniform all around the circumference of the shaft throughout each shaft revolution (disregarding for the time being the minor and constant effect of gravity present when the rotational axis is horizontal as here shown). The fluid pressure in all three recesses 21, 22, 23 and hence in all three balancing chambers 17, 18, 19 connected thereto, is hence continually the same. Because of the equal pressures in chambers 17, 18, 19, the three rollers 11, 12, 13 assume equi-angular positions along the raceway as shown.

Assume now that an unbalance mass is present at some point in the revolving assembly, due to some uncontrollable cause. Such an unbalance mass has here been symbolically indicated as a small additional weight B attached to a point of annular part 1, specifically adjacent the stop 51 marking the center of balancing chamber 17. The unbalance will generate a centrifugal force which throughout each revolution tends to press the recess 21 of the shaft into tight engagement with the inner surface of bearing 3, so that the fluid film thickness is reduced in the corresponding shaft area and the pressure in recess 21 becomes greater while the pressure in the other two recesses 22, 23 grows correspondingly lower. Similar pressure variations are reflected in the three balancing chambers 17, 18, 19, respectively connected with the recesses 21, 22, 23, so that the pressure in chamber 17 is increased and that in chambers 18 and 19 correspondingly decreased. Hence the rollers 12, 13 defining chamber 17 are urged away from each other along the raceway, increasing the volume of chamber 17 and reducing the volumes of chambers 18 and 19. This outward motion of rollers 12, 13 towards roller 11 creates an unbalance reverse from that produced by the mass B, and when the roller displacement has been sufficient to offset the initial unbalance so that the resulting centrifugal force is zero and the shaft is revolving in a centered condition in its bearing, the pressures in the three shaft recesses 21, 22, 23 and hence in the three chambers 17, 18, 19 are equalized so that the rollers 12 and 13 remain relatively stationary in their displaced positions. This condition will last so long as the initial unbalance remains unchanged in amount and in phase (or angular position). Should such a change in amount and/or in phase occur however, a sequence of events generally similar to that described will ensue, and the configuration of the three rollers around the raceway will undergo another shift to meet

75

the changed condition and restore the dynamically balanced, centered, condition of the shaft.

It is found in practice that the system described accomplishes a permanent and continual compensation of a dynamic unbalance with very rapid response, a result attributable in part to the large flow of fluid and to the high pressure under which the fluid is delivered in a fluid bearing, as well as to the direct supply of fluid in parallel to each shaft recess and balancing chamber, by way of a common restricted orifice 47. This parallel supply of fluid is found to result in substantially improved performance characteristics over what is obtained with a serial supply of fluid through the fluid film of the bearing to the balancing chambers as in certain prior systems of the class to which the invention is directed. Moreover, since the bearing recesses 21, 22, 23 are formed in the shaft and hence revolved bodily with the rotating assembly, accurate compensation is had continuously throughout every revolution.

As earlier noted the auxiliary restricted orifices such as 30 shown in the connecting passages 25 may usually be omitted with good results when desired to obtain maximum response speed of the rebalancing system. However, in some cases the insertion of the orifices 30 may be desirable in order to introduce some damping in the response characteristic. This may be especially useful in the case of a substantial gravity force component being present in the system, such as in the horizontal shaft system shown, since such a constant gravity component tends to induce cyclic pressure variations in the balancing chambers as the shaft rotates. Such cyclic pressure variations do not per se tend to produce relative shifting of the balancing rollers, since the mean values of the pressures remain constant. Moreover, normal damping due to the shear of the fluid through the various restricted passages in the fluid flow circuit, including the passages around the rollers, usually suffice to dampen out to a substantial extent the said cyclic variations. However, especially in the case of a low-speed, heavyweight, horizontally mounted revolving assembly, the use of the optional restricted inserts 30 may prove desirable for further damping out any residual vibrations.

The balancing section of the system including the continuous annular raceway or channel containing the plurality of, preferably three, balancing elements in the form of perforate rollers, in combination with the stop means 51, 52, 53 which positively limit the arcuate displacements of the rollers, as shown and described above, is highly advantageous for several reasons. While being simple and inexpensive to construct and assemble, the continuous annular channel ensures optimal transmission of pressure variations through the body of fluid contained therein and hence optimal response to an unbalance; also the available length of displacement of the movable elements is increased for given over-all dimensions. At the same time, the stops positively prevent the straying of the balancing chambers all around the annular channel, which would otherwise result in incorrect operation since each balancing chamber 17, 18, 19 would then be liable to communicate with the wrong shaft recesses 21, 22, 23; said stops however do not substantially interfere with the continuous character of the annular raceway in regard to the transmission of pressure forces. The cylindrical shape of the balancing elements 11, 12, 13 makes them easy to machine to the requisite tolerances and the axial perforations through the elements ensure pressure balance between the opposite ends thereof as well as a self-lubricating effect conducive to smooth floating displacement of the rollers around the raceway to effect the desired compensating shifts.

What is claimed is:

1. The combination with a revolving assembly having a shaft rotatable in at least one bearing, of dynamic balancing means for said assembly comprising a plurality of

chambers, equi-angularly disposed at the periphery of said shaft between said shaft and said bearing, raceway means defined in said assembly coaxially surrounding said shaft; a plurality of balancing elements positioned in the raceway for displacement along arcuate paths therein and defining a plurality of spaces between said elements, equal in number to said chambers; passage means connecting each chamber with a related space, and means for supplying fluid under pressure to said passage means, said fluid under pressure supporting at least partially said shaft; whereby a pressure change occurring in any one of said chambers due to dynamic unbalance of the revolving assembly will induce a compensatory shift in the relative position of said elements.

15 2. The combination with a revolving assembly having a shaft rotatable in a bearing surface, of dynamic balancing means comprising a plurality of equi-angularly disposed chambers recessed in the shaft periphery surrounded by said bearing surface; raceway means defined in said assembly and coaxially surrounding the shaft; a plurality of balancing elements in the raceway displaceable along arcuate paths therein and defining a plurality of spaces between said elements equal in number to said chambers; a passageway connecting each 20 chamber with a related space, fluid supply passage means formed through said bearing surface and other passage means formed through said shaft and communicating with said supply passage means; a plurality of restricted calibrated orifices connecting said other passage means with each of said passageways for supplying pressure fluid in parallel to all pairs of interconnected spaces and chambers; and fluid return passage means formed in said bearing surface and communicating with said chambers.

25 3. In combination with a revolving assembly including a shaft, a bearing for supporting said shaft with a clearance space therebetween, said shaft having a bearing surface formed with a plurality of circumferentially spaced recesses, means defining in said assembly a continuous annular raceway coaxially surrounding the shaft; a plurality of balancing elements in the raceway displaceable along arcuate paths therein and defining a plurality of spaces between said elements; the number of said spaces being equal to the number of said recesses, angularly equispaced stop means positioned in said raceway for limiting the arcuate paths of travel of said elements and thereby preserving the relative disposition of said spaces without substantially restricting the flow section of the raceway; a duct connecting each of said spaces with one of said recesses, respectively, and means 30 for conducting fluid under pressure separately to each of said ducts.

40 4. The combination claimed in claim 3, wherein said ducts include each an axially extending portion formed in said shaft, said portions opening into said raceway 45 at angularly equispaced points substantially radially aligned with said stop means.

45 5. In combination with a revolving assembly including a shaft, a bearing for supporting said shaft with a clearance space therebetween, said shaft having a bearing surface formed with a plurality of circumferentially spaced recesses, means defining in said assembly a continuous annular raceway coaxially surrounding the shaft; a plurality of cylindrical elements in the raceway positioned with their axes parallel to the shaft axis and displaceable along arcuate paths in the raceway in substantially fluid-sealing freely-displaceable relationship with the walls thereof to define with said walls a plurality of arcuate spaces of variable volume; the number of said spaces being equal to the number of said recesses, angularly equispaced stops in the raceway limiting the arcuate paths of travel of said elements and thereby preserving the relative disposition of the spaces defined between said elements without substantially restricting the flow section of the raceway; and duct means connecting each 50 of said spaces with one of said recesses, respectively, and 55 60 65 70 75

means for conducting fluid under pressure separately to each of said duct means.

6. The combination claimed in claim 5, wherein said elements have passages formed therethrough parallel to the axis of the element and interconnecting the opposite end faces thereof.

7. The combination claimed in claim 2, further including a restricted calibrated orifice interposed in the connection from each of said passageways to the related space in the raceway.

10

8. The combination claimed in claim 2, wherein said fluid return passage means include passages recessed in the shaft periphery parallel to the shaft axis and intermediate each pair of adjacent first chambers.
